UNITED STATES PATENT OFFICE.

MAX TAIGMAN, OF NEW YORK, N. Y.

Brake for Electric-Motor-Operated Machines.

1,080,387.

Specification of Letters Patent.

Patented Dec. 2, 1913.

Application filed March 24, 1913. Serial No. 758,419.

To all whom it may concern:

Be it known that I, MAX TAIGMAN, a citizen of the United States, and a resident of the city of New York, borough of Manhattan, in the county and State of New York, have invented a new and Improved Brake for Electric-Motor-Operated Machines, of which the following is a full, clear, and exact description.

10 The present invention relates to improvements in brakes of the character mentioned, and more particularly to brakes combined with a starting box for an electric-motor, or operated in unison therewith, and has 15 among its principal objects, to unify the combined elements and to simplify the construction and arrangement of the parts forming the connective structure between the two principal elements.

20 A further object contemplated by the present invention is to arrange the connective structure to permit the adjustment thereof to various installation conditions.

With these objects in view, the invention 25 consists in providing a pivot for the brake lever supported upon the casing of the starting box, and in providing a series of pivoting connective structures adapted for adjustment to vary the location of the brake 30 pivot relative the casing, to accommodate the location of the brake pulley.

It further consists in constructing and arranging the supporting members for said pivot to vary the operative position of the 35 brake shoe to accommodate the location of the brake pulley.

One embodiment of the present invention is shown in the accompanying drawings, in which—

40 Figure 1 is a perspective view of a starting box, a brake lever operatively connected therewith, and a pivot supporting connecting structure therefor; Fig. 2 is a cross section taken on the line 2—2 in Fig. 1, showing the starting-box case, the mechanism being removed; Fig. 3 is a detail view, on an enlarged scale, showing one of the locking members for the cover of the starting box.

50 As seen in the accompanying drawings, the starting box is provided with integrally-formed upwardly-extending supporting brackets 8. Each bracket is pro-

vided with a screw-hole 9, adjacent one end thereof, and an open-ended slot 10, at the other end thereof. The arrangement of the holes 9 and slots 10, both of which are provided to receive bolts or other suitable fastening members, permits of an adjustment in placing said box on any standing structure, such as a work bench or machine stand. The box is employed to contain a suitable rheostat or other electric-current-controlling mechanism operable by a starting lever 11. The mechanism within the box is exposed when the cover 12 is removed therefrom.

To hold the cover 12 in position, a curved dowel pin 13 is formed integral with said cover, to enter a socket perforation 14 formed in the upper side of the box (see Figs. 1 and 2 of the drawings). The cover 12 is held in position by a spring clip 15, which is rigidly mounted on the under side of the box, and is provided at the forward end with an inclined apron 16, over which the lower edge of the cover 12 passes, to deflect the spring, when moving to its seat, as shown in Fig. 2 of the drawings. To support its weight, the cover 12 is provided with a spur 17, shaped to override and bear upon the inner surface of the under side of said box, when held by the hook shoulder at the junction of the spring clip 15 and the apron 16 thereof.

The starting lever 11 is normally supported by a coil spring 18. To anchor the ends of the spring 18, the bracket 8 adjacent the lever 11 is provided with a flange 19 having a perforation 20, through which an end of the spring is inserted or hooked. The opposite end of the spring 18 is extended around the uppermost of the hooks 21, which hooks are extended from the opposite edges of the lever 11. The lever 11 may thus be inserted within the starting box, so that either of the hooks 21 may be engaged by the spring 18, or, if in the installation it becomes necessary to invert the box from the position shown in Fig. 1, the spring 18 could be reversed and draw upon the hook 21 opposite to that with which it is shown as engaged, the opposite end of said spring being anchored to the standing structure. It will be noted that, in the event of such reversion, arrangement would of necessity be made within the starting box, so that the

lever 11 would rest its circuit contact on the neutral or dead post of the starting box, when moved thereto by the spring 18.

The starting lever 11 is connected directly with the brake lever 22 by means of a rounded rod-like extension 23 and an enlarged circular aperture formed in the exposed end of said lever. The relative variation in size of the extension 23 and the aperture 24 admits of varying the operative angles of the brake lever 22 relative the starting lever 11, without cramping.

At the extreme end of the lever 11, a second aperture 25 is provided to receive the hook end 26 of a connecting rod 27. Said rod is usually connected to a foot treadle, upon which the operator presses when starting the motor for his machine. By operatively connecting the starting lever 11 and the brake lever 22, the pulley 28 of the driving mechanism for a machine is released simultaneously with the starting of the motor supplied from the starting box described. The location of the pulley 28 may be such as to require adjustment of the brake lever 22 relative thereto, in order that a brake shoe 29 may grip the wheel favorably. For this purpose, the bracket shafts 30 and 31 are slidably and rotatably mounted in bearings formed in a boss 32 and a link block 33.

The bearings for the shafts 30 and 31 in the link block 33 are perpendicularly disposed each to the other, and spaced apart lengthwise of said block. By spacing the shaft 31 from the shaft 30, said shaft 31 is permitted to rotate about the center of the shaft 30, to accommodate any desired arrangement for a pivot arm 34. The pivot arm 34 carries a pivot pin 35, upon which the brake lever 22 fulcrums.

Normally, a set screw 36 holds rigidly the shaft 30. When said set screw 36 is loosened, the shaft 30 may be moved lengthwise the boss 32, to extend or retract the service position of the link block 33. The link block 33 is held rigid on the shaft 30 by a set screw 37. When the set screw 37 is released, the block 33 may be rotated in the manner above described. When a set screw 38 is released, the shaft 31 may be rotated in the block 33, or drawn lengthwise therefrom or retracted therethrough.

Having a connective structure to support the brake lever 22, the operation is as follows:—When the starting box and brake are installed, suitable fastening devices are inserted through the perforations 9 and the slots 10. The set screws 37 and 38 are then loosened to release the shafts 30 and 31. The adjustment of the lever 22 to a position favorable for the operation of the brake shoe 29 may now be freely made. The link block 33 being movable lengthwise of the

shaft 30, and the shaft 31 being slidable within the link block 33, the pivot 35 may be longitudinally or laterally varied. If the service positions of the starting box and pulley 28 are angularly related, this is accommodated by rotating the link block 33 on the shaft 30. If the service location of the starting box and pulley 28 varies perpendicularly, this may be accommodated by rotating the pivot arm 34 and the shaft 31 connected therewith, in the block 33. Whenever the favored operative position is attained, the shafts 30 and 31 and the arm 34 connected therewith, are located fixedly in position by setting up the screws 37 and 38.

Having thus described my invention, I claim as new and desire to secure by Letters Patent:—

1. In combination, a starting box for electric motors; a starting lever mounted therein; a brake lever operatively connected with said starting lever; a pivot arm having an elongated pivot shaft and a fulcrum for said brake lever; a link block pivotally mounted on said box; and means for fastening said pivot shaft in said link block to adjust laterally the pivot arm and fulcrum mounted thereon.

2. In combination, a starting box for electric motors; a starting lever mounted therein; a brake lever operatively connected with said starting lever; a pivot arm, having at one end a fulcrum for said lever and at the opposite end an elongated pivot shaft; a boss mounted on said box, bored substantially parallel to said brake lever; a bracket shaft slidably mounted in said bore; and means pivotally uniting said bracket shaft and said pivot shaft.

3. In combination, a starting box for electric motors; a starting lever mounted therein; a brake lever operatively connected with said starting lever; a pivot arm, having at one end a fulcrum for said lever and at the opposite end an elongated pivot shaft; a boss mounted on said box, bored substantially parallel to said brake lever; a bracket shaft slidably mounted in said bore; a pivot block operatively connecting said bracket shaft and said pivot shaft, said block having a plurality of perpendicularly-disposed bearings for said shafts; and fasteners mounted in said block, for fixing in adjusted relation said shafts.

4. In combination, a starting box for electric motors; a starting lever mounted therein; a brake lever operatively connected with said starting lever; a pivot arm having at one end a fulcrum for said lever and at the opposite end an elongated pivot shaft; a boss mounted on said box, bored substantially parallel to said brake lever; a bracket shaft slidably mounted in said bore; a pivot

block operatively connecting said bracket
shaft and said pivot shaft, said block hav-
ing a plurality of perpendicularly-disposed
bearings for said shafts; and a plurality of
5 set screws mounted in said pivot block to fix
in adjusted position said shafts therein.

In testimony whereof I have signed my

name to this specification in the presence of
two subscribing witnesses.

MAX TAIGMAN.
